METHOD OF MAKING MIXED DIGLYCERIDE

Norris D. Embree and George Y. Brokaw, Rochester, N. Y., assignors to Eastman Kodak Company, Rochester, N. Y., a corporation of New Jersey

No Drawing. Application August 6, 1952,
Serial No. 303,006

13 Claims. (Cl. 260—410.8)

This invention relates to methods of processing fatty triglycerides and to fatty triglyceride derivatives obtained thereby.

Animal and vegetable fats and fatty oils consist in large part of fatty triglycerides, i. e. glyceryl fatty acid triesters. For many uses, it is desirable to modify the chemical or physical properties or both of such fatty triglycerides by forming derivatives or mixtures of derivatives of such fatty triglycerides to obtain products suitable for plasticizers, film-forming fats, easily digestible fats or the like.

Most of the naturally occurring fats and fatty oils are relatively complex mixtures and similarly the derivatives of such fats and fatty oils are mixtures of materials not readily separable by usual methods and not amenable to conventional identification techniques. Thus, in derivatives of such fats and fatty oils, the characteristics of the products are apparently dependent upon the interrelationships between many diverse factors such as relative proportions of closely related components, isomeric ratios, state of crystallization of components and other factors not readily identifiable. As a consequence, fat technology is in large measure empirical and the composition of fatty mixtures is a function of the method of processing employed to a significant extent.

It is accordingly an object of this invention to provide new methods of processing fatty triglycerides to obtain new and useful compositions of fatty triglyceride derivatives.

It is also an object of this invention to provide highly effective methods of preparing improved compositions containing a substantial proportion of acylated glyceryl fatty acid partial esters.

Another object of the invention is to provide new methods of converting fatty triglycerides in high yield to products having quite different properties than the fatty triglycerides from which they were prepared.

Another object of the invention is to provide methods for making fatty triglyceride derivatives by concomitant alcoholysis and ester-interchange.

Another object of the invention is to provide compositions of improved chemical and physical characteristics and having an average composition corresponding to monoacyl monoglycerides.

Another object of the invention is to provide an improved method of making derivatives of triglycerides of higher fatty acids.

Another object of the invention is to provide a simple and effective method of converting naturally occurring fatty triglycerides to compositions containing a substantial proportion of monoaceto monoglycerides and for obtaining material having an average composition corresponding to monoaceto monoglycerides but differing in properties from conventional monoacetomonoglyceride compositions.

Another object of the invention is to provide improved compositions having an average composition corresponding to monoacetoglyceryl monostearate.

2

Other objects will be apparent from the description and claims which follow.

These and other objects are attained by means of this invention as described more fully hereinafter with particular reference to certain preferred embodiments thereof.

The fatty triglycerides which are processed in accordance with this invention to give products having greatly modified physical and chemical properties include both solid fats and fatty oils, whether obtained from natural sources or synthetically prepared. The invention is of particular utility in processing the triglycerides of the fat-forming higher fatty acids having at least eight carbon atoms in the fatty acid radical. Of greatest practical importance is the processing of the naturally occurring fatty triglycerides as found in animal fats such as lard, or vegetable oils such as cottonseed oil, soybean oil, peanut oil, coconut oil and the like.

In accordance with this invention, the fatty triglycerides, either in purified form or as mixtures of triglycerides together with other constituents of fats and fatty oils, are subjected to concomitant alcoholysis and ester-interchange by co-reacting such fatty triglycerides, glycerine and an acylated glycerine in a reaction mixture containing a basic transesterification catalyst whereby a reaction product containing a substantial proportion of acylated glyceryl fatty acid partial ester is obtained. The degree of acylation of the fatty triglyceride is dependent upon the molar ratio of acylated glycerine to glycerine as well as the extent of acylation of the acylated glycerine, and the degree of conversion of the fatty triglyceride is a function of the ratio of fatty triglyceride to the combined amount of glycerine and acylated glycerine.

The reaction is promoted by the presence of a small amount of a basic transesterification catalyst in the reaction mixture. Any of the well-known basic transesterification catalysts can be used including the alkali metals, alkali metal hydrides, alkali metal glyceroxides and the like, with the basic metal hydroxides such as the alkali metal hydroxides and particularly the bivalent metal hydroxides being desirably employed. Thus, suitable basic transesterification catalysts include sodium metal, sodium hydride, sodium and potassium glyceroxides, sodium hydroxide, potassium hydroxide, calcium hydroxide, strontium hydroxide and similar well-known basic transesterification catalysts. The amount of catalyst can be varied in accordance with usual transesterification practice, with amounts of from about 0.001% to about 1% and particularly from about 0.005% to about 0.1% by weight based on the total weight of the reaction mixture being preferably employed.

The reaction is effected at elevated temperatures for optimum results with temperatures of at least 180° C. and particularly from about 200° C. to about 280° C. being eminently suitable. The maximum temperature suitable for operations at ordinary pressures is the reflux temperature of the reactants. The reaction time is usually from about 15 minutes to about 6 hours depending upon the ratio of the reactants, concentration of catalyst, reaction temperature and similar variables affecting the speed of the reaction.

The glycerine and acylated glycerine can be charged separately but particularly good results are obtained by prereacting the acylated glycerine and the excess glycerine under the reaction conditions, especially in the case of an acyl triester of glycerine, to give a premixture of glycerine with acylated mono-, di- and triesters of glycerine. The acylated glycerine can be monoacyl glycerine, diacyl glycerine or triacyl glycerine or mixtures of two or more of such materials in which the acyl radicals contain from 2 to 6 and desirably 2 to 4 carbon atoms. Thus suitable acylated glycerines include monoacetin, diacetin, triacetin or mixtures thereof; tributyrin, dibutyrin, monobutyrin or

mixtures thereof; tricaproin, dicaproin, monocaproin or mixtures thereof, or mixtures of any of these or similar acylated glycerines having from 2 to 6 carbon atoms in the acyl radicals with each other.

The reaction mixture obtained usually consists of unreacted glycerine, higher fatty acid triglyceride and acylated glycerine in admixture with substantial amounts of monoacyl monoglycerides, diacyl monoglycerides and monoacyl diglycerides. The resulting reaction product can be used directly if desired, but preferably the unreacted glycerine, fatty triglyceride and acylated glycerine are stripped out and desirably the stripped product is distilled or otherwise separated to give a material having an average composition corresponding to monoacyl monoglyceride. The unreacted glycerine, acylated glycerine and triglycerides can be separated out by solvent extraction, fractional crystallization of the monoacyl monoglycerides from solvent such as petroleum ether at lowered temperatures such as 4° C. or lower, or similar well-known separation procedure, with vacuum distillation and particularly thin film high vacuum distillation at pressures below 300 microns Hg. and temperatures of 160°-185° C. or higher being particularly effective to give a product having an average composition corresponding to monoacyl monoglyceride. If desired, however, the product mixture stripped of unreacted glycerine, fat and acylated glycerine can be used without further separation, or varying fractions thereof can be used depending upon the product characteristics desired.

The invention is illustrated by the following examples of preferred embodiments thereof, it being understood that the examples are not intended to limit the scope of the invention unless otherwise specifically indicated.

Example 1

A mixture of 90 parts by weight of glycerine, 682 parts by weight of hydrogenated lard and 428 parts by weight of triacetin was charged into a pot reactor equipped with a stirrer. To the mixture was added strontium hydroxide catalyst amounting to 0.12% by weight based on the weight of lard. The mixture was heated at 250° C. and stirred for 5 hours. The resulting reaction mixture was then subjected to distillation on a high vacuum centrifugal still with the unreacted glycerine and glyceryl acetates being stripped out as a strip cut at 135° C. and a pressure below 300 microns Hg. and product recovered as the fraction distilling between 165° and 185° C. The product was obtained in a yield of 46.8% based on the lard weight and was a film forming, plastic material softening at 35° C. and melting at 36° C. Similar results are obtained with other triglyceride fats such as other animal fats and vegetable oils and with triacetin or other acylated glycerines as described hereinabove.

Example 2

A mixture of monoaceticin, diacetin, triacetin and glycerine was prepared by heating a mixture of 244 g. of glycerine, 576 g. of triacetin and 0.065 g. of calcium hydroxide for 90 minutes at 255-260° C. To the resulting mixture was added 680 g. of hydrogenated lard and 0.05 g. of calcium hydroxide. This reaction mixture was then heated for 90 minutes at 265° C. after which one-third of the charge was drawn off and vacuum distilled. The distillate fraction obtained at 185° C. amounted to a yield of 63.3% based on the lard. This product had a softening point of 41° C., a melting point of 42-45° C., a hydroxyl value of 118.7 and formed a film which could be bent 180° for 24 times at 27° C. before cracking.

The remaining two-thirds of the charge was heated for an additional 90 minutes, after which half of the product was removed from the reactor and vacuum distilled. The product fraction obtained at 185° C. amounted to a yield of 64.7% based on the lard weight and had a softening point of 38° C., a melting point of 41-43.5° C., a saponi-

fication number of 291 and withstood twenty bends in film form at 27° C. before cracking.

The remainder of the charge was heated for an additional 3 hours at 265° C. and the product fraction obtained by vacuum distillation at 185° C. represented a yield of 61.2% based on the weight of lard. This product had a softening point of 42° C., a melting point of 43-56° C., a hydroxyl value of 119 and a film bend number of 24.

Example 3

A reaction product was prepared by co-reacting glycerine, triacetin and lard in the ratio of 1 mole of glycerine to 1 mole of triacetin, and 6 moles of glycerine plus triacetin to one mole of lard, using 0.008% by weight of calcium hydroxide based on the total charge as catalyst. The distilled product obtained from a 6 hour reaction at 265° C. amounted to a yield of 71.2% based on the lard and had a softening point of 40° C. and a melting point of 42-42.5° C.

Example 4

A mixture of 184.2 grams of glycerine, 872.8 grams of triacetin and 873.6 grams of hydrogenated lard was heated for 3 hours at 265° C. in the presence of 0.008% by weight of calcium hydroxide based on the total charge. The product fraction obtained by vacuum distillation at 185° C. amounted to a 49.4% yield based on the lard and had a softening point of 35° C., a melting point of 38° C., a hydroxyl value of 108 and a saponification number of 317.

Example 5

Hydrogenated lard, triacetin and glycerine were reacted in the same molar proportions as in the preceding example using 0.02% by weight of sodium hydroxide, based on the total charge, as catalyst and a reaction temperature of 220° C. for 3 hrs. The distilled product obtained had a melting point of 36-39° C. and a hydroxyl value of 127.

Similar results are obtained with other fatty triglycerides, acylated glycerines and basic transesterification catalysts employing concentrations and reaction conditions as described hereinabove.

The compositions preferably obtained have an average composition corresponding to monoacyl monoglycerides. The products can be varied from plastic solids at room temperature in the case of the materials having an average composition corresponding to monoacyl glyceryl monostearates, such as the monoaceto glyceryl monostearates obtained by the co-reaction of lard with acetylated glycerine and glycerine, to liquids which remain fluid at temperatures below 0° C. in the case of the materials having an average composition corresponding to monoacyl glyceryl monooleates, such as the monoaceto glyceryl monooleates obtained by the co-reaction of peanut oil with acetylated glycerine and glycerine. Furthermore the properties of the product can be varied greatly by controlling the degree of acetylation, since, for example, products containing a large amount of monostearin in admixture with a smaller amount of monoaceto and diaceto monostearins have a melting point considerably above room temperature whereas products having an average composition corresponding to diacetomonostearin have a melting point of about 25° to 30° C. The plastic solids form edible coherent films useful as food coatings, and the liquids are useful as food oils, plasticizers and the like. Materials having modified properties can be obtained by blending various monoacyl monoglycerides with each other or with other compatible fatty materials.

Although the invention has been described in considerable detail with reference to certain preferred embodiments thereof, it will be understood that variations and modifications can be effected within the spirit and scope of the invention as described hereinabove and as defined in the appended claims.

We claim:

1. The method of processing a fatty triglyceride which comprises effecting concomitant alcoholysis and ester-interchange between a fatty triglyceride wherein the fatty acid radicals each contain at least eight carbon atoms, glycerine and an acylated glycerine wherein the acyl radicals each contain from two to six carbon atoms by co-reacting said fatty triglyceride, glycerine and acylated glycerine in a reaction mixture containing a basic transesterification catalyst to produce a reaction product containing a substantial amount of glyceryl partial ester containing a free hydroxyl group, one of said acyl radicals and one of said fatty acid radicals.

2. The method of processing a fatty triglyceride which comprises co-reacting, in a reaction mixture containing a basic transesterification catalyst, a mixture of fatty triglyceride wherein the fatty acid radicals each contain at least eight carbon atoms, glycerine and an acyl triester of glycerine wherein each acyl group contains from two to six carbon atoms, the combined molar proportions of said acyl triester and said glycerine being greater than the molar proportion of said fatty triglyceride, and thereby effecting concomitant alcoholysis and ester-interchange to produce a reaction product comprising an admixture of mono-fatty acid monoacyl diesters of glycerine, mono-fatty acid diacyl triesters of glycerine, di-fatty acid monoacyl triesters of glycerine, glyceryl fatty acid monoesters, and glyceryl fatty acid diesters wherein the acyl groups are said acyl groups from said acyl triester and the fatty acid groups are said fatty acid radicals from said fatty triglyceride, the composition of said reaction product being correlated to the ratio of the reactants in said reaction mixture.

3. The method of processing fatty triglyceride which comprises co-reacting, in a reaction mixture containing a basic transesterification catalyst, a mixture of fatty triglyceride wherein each fatty acid radical contains at least eight carbon atoms, glycerine and an acyl triester of glycerine wherein the acyl groups contain 2 to 6 carbon atoms, said acyl triester and said glycerine being present in substantially equimolar proportions, said co-reacting causing concomitant alcoholysis and ester-interchange and thereby producing a reaction product containing a substantial proportion of monoacyl mono-fatty acid esters of glycerine wherein the acyl groups are from said acyl triester and the fatty acid groups are from said fatty triglyceride.

4. The method of processing fatty triglyceride which comprises co-reacting a fatty triglyceride wherein each fatty acid radical contains at least eight carbon atoms, glycerine and triacetin in the presence of a basic transesterification catalyst and thereby effecting concomitant alcoholysis and ester-interchange effective to produce a reaction product comprising a predominant amount of monoaceto mono-fatty acid diesters of glycerine and a minor amount of diaceto mono-fatty acid triesters of glycerine in admixture with di-fatty acid monoaceto triesters of glycerine, glyceryl fatty acid monoesters and glyceryl fatty acid diesters wherein the fatty acid radicals are from said fatty triglyceride.

5. The method of processing fatty triglycerides which comprises co-reacting a fatty triglyceride selected from the class consisting of animal triglycerides and vegetable triglycerides with glycerine and an acyl triester of glycerine wherein the acyl groups contain from 2 to 6 carbon atoms, in the presence of a basic transesterification catalyst, said fatty triglyceride, glycerine and acyl triester of glycerine being present in correlated amounts with said acyl triester and said glycerine having a predetermined molar ratio and a combined molar amount greater than the molar amount of said triglyceride, said co-reacting effecting concomitant alcoholysis and ester-interchange whereby a reaction product is obtained comprising monoacyl mono-fatty acid diesters of glycerine, diacyl mono-fatty acid triesters of glycerine and monoacyl di-fatty acid

triesters of glycerine in a predetermined ratio correlated to said molar ratio of glycerine and acyl triester.

5 6. The method of processing triglyceride which comprises co-reacting a fatty triglyceride wherein each fatty acid radical contains at least eight carbon atoms, glycerine and triacetin in the presence of a basic transesterification catalyst, said glycerine and said triacetin being present in substantially equimolar amounts in excess of the molar proportion of fatty triglyceride, said co-reacting causing concomitant alcoholysis and ester-interchange effective to produce a reaction product comprising a mixture of glyceryl esters including a substantial proportion of product having an average composition corresponding to monoaceto mono-fatty acid diester of glycerine.

10 7. The method of processing triglyceride which comprises co-reacting a fatty triglyceride wherein each fatty acid radical contains at least eight carbon atoms, glycerine and acylated glycerine wherein each acyl group contains from two to six carbon atoms in a reaction mixture containing a basic transesterification catalyst and thereby forming a reaction product including a substantial proportion of monoacyl mono-fatty acid diester of glycerine, and separating by thin film high vacuum distillation said diester from said reaction product.

15 8. The method of processing fatty triglyceride which comprises co-reacting a fatty triglyceride wherein each fatty acid radical contains at least eight carbon atoms, glycerine and an acyl triester of glycerine wherein each acyl group contains from two to six carbon atoms in a reaction mixture containing a basic transesterification catalyst to effect concomitant alcoholysis and ester-interchange and thereby producing a reaction product comprising a substantial proportion of monoacyl mono-fatty acid diester of glycerine, and separating said diester from said reaction product.

20 9. The method of processing fatty triglyceride which comprises co-reacting substantially equimolar proportions of glycerine and an acyl triester of glycerine, wherein the acyl groups contain from 2 to 6 carbon atoms, with a lesser amount of fatty triglyceride wherein each fatty acid radical contains at least eight carbon atoms in a reaction mixture containing a basic transesterification catalyst, said co-reacting being effective by concomitant alcoholysis and ester-interchange to produce a reaction product comprising a substantial proportion of monoacyl mono-fatty acid diester of glycerine, and separating from said reaction product a material having an average composition corresponding to said diester.

25 10. The method of processing a triglyceride of higher fatty acids which comprises co-reacting a triglyceride of higher fatty acids having an average composition corresponding to glyceryl tristearate, glycerine, and an acyl triester of glycerine, wherein the acyl groups contain from 2 to 6 carbon atoms, in a reaction mixture containing a basic transesterification catalyst, and separating from the resulting reaction product a material having an average composition corresponding to monoacyl glyceryl monostearate.

30 11. The method of processing triglycerides which comprises co-reacting a fatty triglyceride containing fat-forming fatty acid radicals having more than 8 carbon atoms, glycerine and an acetylated glycerine mixture comprised of monoacetin, diacetin and triacetin, in the presence of a basic transesterification catalyst, and thereafter separating from the resulting reaction mixture by thin film high vacuum distillation a composition containing a substantial amount of glyceryl partial ester containing a free hydroxyl group, an acetyl radical and one of said fat-forming fatty acid radicals.

35 12. The method of producing acetylated fatty compositions which comprises co-reacting a fatty triglyceride wherein the fatty acid radicals each contain at least 8 carbon atoms, glycerine and an acetylated glyceride selected from the group consisting of (A) triacetin and

(B) a mixture of monoacetin, diacetin and triacetin, in the presence of a basic transesterification catalyst, the molar proportions of the reactants being correlated to produce a reaction mixture comprised predominantly of glyceryl partial esters containing at least one free hydroxyl group including a substantial amount of glyceryl partial ester containing a free hydroxyl group, an acetyl radical and one of said fatty acid radicals.

13. The method of producing acetylated fatty compositions which comprises co-reacting a fatty triglyceride wherein the fatty acid radicals each contain at least 8 carbon atoms, glycerine and an acetylated glyceride selected from the group consisting of (A) triacetin and (B) a mixture of monoacetin, diacetin and triacetin, in the presence of a basic transesterification catalyst, the molar proportions of the reactants being correlated to produce a reaction mixture comprised predominantly of glyceryl partial esters containing at least one free hy-

droxyl group, and thereafter separating from said reaction mixture by thin film high vacuum distillation a composition containing a substantial amount of glyceryl partial ester containing a free hydroxyl group, an acetyl radical and one of said fatty acid radicals.
